CENTER ORNAMENT FOR ASH TRAY OR SIMILAR ARTICLE

Russell L. Rust, San Marino, Calif.

Application June 13, 1949, Serial No. 3,248

Term of patent 3½ years

(Cl. D29—23)

To all whom it may concern:

Be it known that I, Russell L. Rust, a citizen of the United States, residing at San Marino, in the county of Los Angeles and State of California, have invented a new, original, and ornamental Design for Center Ornament for Ashtray or Similar Article, of which the following is a specification, reference being had to the accompanying drawing, forming a part thereof.

Figure 1 is a perspective view of a center ornament for an ashtray, showing my new design. The broken line showing is for illustrative purposes only.

I claim:

The ornamental design for a center ornament for ash tray or similar article, substantially as shown and described.

RUSSELL L. RUST.
